UNITED STATES PATENT OFFICE.

CHARLES E. DOTY, OF NEW YORK, N. Y.

INSTRUMENT FOR USE IN RAISING AND LINING RAILROAD-TRACKS.

1,199,059.

Specification of Letters Patent. Patented Sept. 26, 1916.

Application filed April 30, 1915. Serial No. 24,862.

To all whom it may concern:

Be it known that I, CHARLES E. DOTY, a citizen of the United States, and a resident of the borough of Bronx, city, county, and 5 State of New York, have invented certain new and useful Improvements in Instruments for Use in Raising and Lining Railroad-Tracks, of which the following is a specification.

10 My invention relates to improved constructions in surveying instruments for use in raising and lining railroad tracks.

One of the objects of my invention is to construct supports for optical instruments 15 so as to make them readily adapted to fit upon the rails of a railroad track, to the end that the vertical hair-line of the optical instruments supported thereby will fall directly in line with the gage side of the rail.

20 Another object of my invention is to so construct target supporting means that it may be readily mounted on the track-rail so that the vertical line marked on the target which is used for lining the track will be in 25 line with the gage side of the rail.

Other objects will appear from the following specification and claims.

Referring to the drawings which form a part of my specification; Figure 1 is an elevation showing the position and use of the 30 instruments in bringing the track to a surface or taking the sags out of the track. Fig. 2. is a plan showing the position and use of the instruments in performing the 35 operation known as lining the track. Fig. 3. is a side elevation of my improved means for supporting the optical instrument upon a rail and tie of the track. Fig. 4. is an end view of the instrument on its improved 40 mounting, the lower portion being in section on line 4—4 of Fig. 3. Fig. 5. is an elevation of the target supporting means used in lining the track, a portion of the rail being shown in elevation. Fig. 6. is a plan view of 45 the structure shown in Fig. 5. the rail being removed. Fig. 7. is a side view of the structure shown in Fig. 6.

In the drawings, like reference characters refer to like parts.

50 A is a conventional telescope or theodolite provided with the usual vertical and horizontal cross hairs, B is a conventional construction of a supporting frame 3 and turn table 4 which is mounted in a conventional way upon its support so that the telescope or theodolite may be turned both in a horizon-

tal and in a vertical plane. The usual spirit levels as indicated at 5 and 6 are also provided, so that the instrument may be brought into a true adjustment. 60

In order to support the instrument upon a rail C and tie D of a track, I provide a structure consisting preferably of three legs, 10, 11 and 12 each of which is pivoted at 10', 11', and 12' to the underside of a fixed plate 65 2, to which the turn table 4 of the optical instrument is pivoted. Leaf springs 13 and 14 are secured at one end to the outer sides of each of the legs 10 and 11, the free ends of the springs being adapted to press against 70 the outer edge of the head 7 of the rail C when the instrument is in position. U shaped guides 13' and 14' are secured to the outer side of the bar 15 through which springs 13 and 14 extend. In the bridge 75 portion of the guides are set screws 13^b and 14^b which operate to adjust the position of the springs in order to adapt them to properly clamp any size of rail-head. A bar 15 preferably of wood is secured to the ends of 80 the legs 10 and 11, the underside of the bar being beveled at 16 as shown, and is adapted to rest upon the upper surface of the rail head. Upon the inner sides of each of the legs 10 and 11, I secure fixed arms 17 and 18. 85 A leaf spring 19 which is bent at its center 20 to engage the under side of the rail head is secured at each end 21 and 22 respectively to the arms 17 and 18. The leg 12 is pivoted at 12' so as to have a movement at right angles 90 to the plane of the two legs 10 and 11. A steel rod 25 screw-threaded at one end as indicated at 27 and having a thumb-screw 28 at its upper end, and pointed at 26 at its lower end is mounted in any suitable way, 95 preferably as shown in Fig. 4., through perforated lugs 8 in order to be readily adjusted in the direction of the length of the leg 12.

In Figs. 5, 6 and 7, I have shown the construction of the target which is used in the operation of "lining" the track. The target mount consists of a block 30 having a spirit level 31 counter-sunk in the center of the block and provided with two steel leaf springs 32 and 33 fastened to one of its sides and with a solid depending portion 34 fastened to its other side. The springs pass through a guide 32^a which has a set screw 33^a in the bridge thereof so that the block 30 100 can be supported on rail heads of varying size. To the block 30 is fastened by nails or 105

screws or in any suitable way a vertical plate 35 on a face of which is a line 41 drawn perpendicularly to the under surface of the block 30 at the point of intersection of the 5 depending portion 34 with the under surface of the said block 30. On this vertical plate is also drawn a line or lines 42 parallel to the under surface of the block 30. These vertical and horizontal lines are known as 10 the "target lines" of the target. The block 30 is fitted upon the top of the rail and held thereto by means of the springs 32 and 33 clamping the head of the rail between them and the inner side of projecting portion 34, 15 which latter abuts against the gage side of the rail.

The manner of using the instrument in the operation of "lining" the track, will now be described.

20 Referring to Fig. 2., the two fixed legs of the instrument are placed on the rail, the shoe portion resting on the top thereof, the springs 13, 14 and 19 holding the two legs rigidly in place upon the rail as clearly 25 shown. The third leg rests upon the tie and is held in position by means of the point 26 of the adjusting rod 25 being forced a short distance into the tie, the height of the third leg being first adjusted by means of the 30 screw connection between it and the rod 25 as described. When the table and optical instrument are level, that fact will be indicated by the spirit levels 5 and 6 placed thereon. Targets as illustrated in Figs. 5, 35 6 and 7 are placed upon the rail, the reference target as indicated at R in Fig. 2 and the working target, as indicated at W in Fig. 2, the vertical "target lines" being coincident with the line of the gage side of the 40 rail. The operator upon looking through the instrument at the target marked R will observe that the hair-line of the optical instrument (which is directly in line with the gage side of the rail) coincides with the vertical 45 line of the reference target R (which vertical line also coincides with the gage side of the rail). The track at the point W is then swung by workmen by means of lining bars or other suitable means into line 50 until the vertical line of both targets and the vertical hair-line of the optical instruments coincide, which fact will be observed by the operator. This operation is repeated at intervals along the track until the entire 55 line of track is adjusted into a perfect line.

My improved instrument may also be used in bringing the track to a surface by taking the sags out of the track. This is accomplished by setting the optical instrument as 60 previously described, at one end of the sag in the track as illustrated at H in Fig. 1. The reference target consisting of vertical adjustable rods as indicated at R' in Fig. 1, is adjusted so that the horizontal line of this target is at a height from the track equal to

the height of the horizontal hair-line of the telescope and is set at the other end of the sag. A similar target marked S set at the same height as the reference target is placed at intermediate points between the instrument and the reference target. The track is raised until the horizontal line of the working target and the horizontal hair-line of the telescope coincide. When this operation is finished, the track is on a true grade. This 70 operation is repeated at intervals along the track between the telescope and the reference target. 75

One of the particular features of my invention is that it consists of instruments so constructed that they can be operated by the ordinary track workman who can obtain accurate results without the necessity of having the engineering knowledge that has heretofore been necessary to accomplish this 80 work in an accurate manner.

The work may be done very quickly on account of the fact that the workmen who are tamping the track are not in line of sight and therefore they do not have to wait until the track is raised. By the use of my instruments, the line and grade stakes only have to be set about 1000 feet apart, while by prior methods they have been set 100 feet apart. If a sag is only 2000 feet long 90 it can be taken out by setting the instrument in the center of the sag, adjusting the rods to cover the rays at a point where the instrument is set. No stakes will be required for sags of 2000 feet or less. 95

What I claim as new and desire to secure by Letters Patent, is:—

1. A support for holding an optical instrument consisting of a head, two fixed legs pivoted thereto, a third and longer leg also pivoted to the head and provided with a screw attachment, means for adjusting the said screw attachment upon the third leg so that the vertical hair-line of the optical instrument will fall directly in line with the 110 gage side of the rail.

2. A support having fixed legs of equal length provided with a supporting shoe between them and a longer leg provided with a screw extension. 115

3. A support provided with stationary legs having a shoe mechanism at the bottom thereof provided with clamping means to hold the same on a rail head. 120

4. A support provided with stationary legs having a shoe mechanism at the bottom thereof provided with adjustable clamping means to hold the same on a rail-head.

5. A support provided with stationary legs having a shoe mechanism at the bottom thereof provided with adjustably mounted spring clamping means to hold the same on a rail head. 125

6. A support for holding an optical instrument consisting of a head, two fixed legs 130

pivoted thereto, a third and longer leg also pivoted to the head and provided with a longitudinally adjustable attachment, means for adjusting the said attachment upon the 5 third leg so that the vertical hair line of the optical instrument will fall directly in line with the gage side of the rail.

In witness whereof I have hereunto set my

hand at the borough of Manhattan, city and State of New York, this 19th day of April, 1915.

CHARLES E. DOTY.

In presence of—

ETHEL D. BACON,
JOHN J. RANAGAN.
